UNITED STATES PATENT OFFICE.

MARCUS B. BEHRMAN, OF NEW YORK, N. Y., ASSIGNOR TO LOX SEAL CORPORATION, OF BROOKLYN, NEW YORK, A CORPORATION OF NEW YORK.

LATHER BRUSH.

Application filed July 22, 1922. Serial No. 576,679.

To all whom it may concern:

Be it known that I, MARCUS B. BEHRMAN, a citizen of the United States, and a resident of New York city, in the county of New York and State of New York, have invented certain new and useful Improvements in Lather Brushes, of which the following is a specification.

The invention relates to improvements in lather brushes of the type comprising a handle, a ferrule receiving the threaded shank of the handle and a bunch of bristles or the like bound together at the knot end thereof and permanently secured within the lower end of the ferrule by a cementitious material. Lather brushes of the construction described possess the disadvantage that the knot end of the bunch of bristles being permanently secured within the ferrule, the bunch may not be subjected from time to time, as may be necessary or desirable, to the process of sterilization without injury to the ferrule. In many instances also the handle has been permanently secured to the ferrule, and hence obviously the brush could not be subjected to a boiling process for the purpose of sterilizing the bristles without injury to both the ferrule and handle. Other constructions of lather brushes have also been well known.

In accordance with my present invention I provide a ferrule and a bunch of bristles whose knot end is seated within the ferrule in a manner permitting of the separation, whenever desired, of the bunch of bristles from the ferrule, and I secure the bunch of bristles in rigid relation to the ferrule by means of a threaded head having a central vertical operating stem by means of which the head may be screwed into the ferrule and against the knot end of the bunch with sufficient firmness to bind the bunch of bristles in fixed relation to the ferrule. The handle for the brush is screwed into the outer end of the ferrule and is chambered to pass over the operating stem on the binding head. One advantage of my invention is that the head which is screwed against the knot end of the bunch of bristles is a flat solid head of disk character which may be screwed to position either with the use of a screw-driver or manually with the thumb and finger and that said head lies low down in the ferrule and does not interfere with the screwing of the shank end of the handle into the ferrule in

the usual and ordinary way. The handle is not subjected, in accordance with my invention, to any strain so far as securing the bunch of bristles in place is concerned.

I illustrate in the accompanying drawings a preferred embodiment of my invention, not intending, however, in every instance to be limited to all of the details and proportions of the parts thereof shown, and the invention will be fully understood from the detailed description hereinafter presented, reference being had to the accompanying drawings, in which:

Fig. 1 is a side elevation of a lather brush constructed in accordance with and embodying the invention;

Fig. 2 is a central vertical section through the same, and

Fig. 3 is a side elevation, partly in section and partly broken away, showing the several parts of the brush as juxtaposed for assembly to produce the brush shown in Figs. 1 and 2.

In the drawings, 10 designates the handle, 11 the ferrule and 12 the bunch of bristles or the like, the knot ends of the bristles being firmly secured together by rubber or other material to form a knot 13 which is closely encompassed by a securing metal band 14 whose sides converge downwardly and inwardly and form a downwardly and inwardly inclined and slightly convexed exterior seating surface 15 extending entirely around the band.

The handle 10 may be of any suitable outline adapted to be conveniently grasped by the hand, and said handle at a suitable distance below its upper end is formed with an annular shoulder 16, below which the handle is constructed with a threaded portion or shank end 17. Within the handle 10 is formed a vertical chamber 18 which extends upwardly from the lower end of the portion 17 a suitable distance for serving the purposes hereinafter described. The handle 10, except for the presence of the chamber 18, may be considered as of ordinary construction.

The ferrule 11 has a screw-thread 19 extending downwardly to near the lower end of the ferrule, and below this thread 19 the ferrule is formed with a chamber to receive the band 14 on the knot end of the bunch and with an opening 20 through which the bristles of the bunch project and which is

surrounded by a vertical wall 21 extending below the lower edge of the band 14 and closely engaging the bristles adjacent to said band. Within the chamber at the lower end 5 of the ferrule 11 is formed an annular shoulder 22 which is at the upper end of the opening 20 and extends laterally therefrom and serves as a seat for the lower edge of the band 14, whose upper portion is disposed 10 within the lower chamber of the ferrule and terminates adjacent to the lower end of the thread 19, as shown in Fig. 2.

The bunch of bristles is introduced downwardly through the ferrule 11 and the band 15 14 seats itself upon the shoulder 22, and thereupon my invention provides means for binding the bunch in rigid relation to the ferrule, said means comprising a binding head or disk 23 which is formed with a peripheral screw-thread 24 and has a central upwardly extending operating stem 25, this stem preferably being formed at its upper part with a milled surface 26 and a screw-driver slot 27. The binding head 23 and its 20 stem 25 may be formed of any suitable material and I have found it convenient to make the same in one integral piece of metal. The binding head 23 is adapted to be screwed into the thread 19 of the ferrule 25 and down against the upper end of the knot 30 13 and band 14 or to the position shown in Fig. 2, and when in this position the head 23 firmly binds the band 14 against its seat 22 and thereby secures the bunch of bristles 35 in rigid relation to the ferrule. The head 23 may be screwed downwardly into the ferrule either manually, as by the thumb and finger applied to the stem 25, or by means of a screw-driver applied to the slot 40 27 in said stem. I prefer to make the stem 25 of substantial length, as shown, so that it may be provided with the milled surface 26 for convenience in manually positioning 45 and removing the head 23. After the bunch 50 of bristles has been secured in place by means of the head 23, the handle 10 may then be screwed into the upper or outer end of the ferrule 11 in the usual way, and in applying the handle to position the chamber 18 thereof will slip downwardly over the upwardly projecting portion of the stem 25, said stem being less in diameter than the chamber 18 and therefore not interfering with the application of the handle to position 55 in the ordinary way.

Should it be desired to separate the parts of the brush for the purpose, for illustration, of sterilizing the bunch of bristles, the handle will be unscrewed from the ferrule 60 and the binding head 23 will then be unscrewed from the ferrule and consequently away from the bunch, after which, by reversing the ferrule, the bunch of bristles 65 may be caused to drop through the normally upper end thereof. After the bristles have

been sterilized, the parts of the brush may be again assembled, the bunch being introduced downwardly through the ferrule 11 until the band 14 seats itself against the shoulder 22, and the binding head 23 then 70 being applied to position, after which the handle 10 will be restored to its position as before.

The stem 25 may be of any length desired but preferably should be of the character 75 shown. With less convenience the stem 25 may be short, and in that event it would on the positioning of the binding disk pass into the ferrule beyond the grasp of the fingers and a screw driver or the like would have to 80 be applied to the stem for finally binding the disk against the knot of the bunch.

What I claim as my invention and desire to secure by Letters-Patent, is—

1. A lather brush comprising a bunch of 85 bristles or the like having a knot-end encompassed by a metal band, a ferrule having an inner screw thread and in its lower portion a seat for said band, a threaded flat binding disk screwed into the lower portion 90 of said ferrule against the knot of the bunch, and a handle having a threaded shank end screwed into the thread of the ferrule at the upper end portion thereof and also a shoulder to engage the upper edge of the 95 ferrule and arrest said shank end above said disk, said disk having a central upwardly extending operating stem by means of which the disk may be screwed to position.

2. A lather brush comprising a bunch of 100 bristles or the like having a knot-end encompassed by a metal band, a ferrule having an inner screw thread and in its lower portion a seat for said band, a threaded flat binding disk screwed into the lower portion 105 of said ferrule against the knot of the bunch, and a handle having a threaded shank end screwed into the thread of the ferrule at the upper end portion thereof and also a shoulder to engage the upper edge of the 110 ferrule and arrest said shank end above said disk, said disk having a central upwardly extending operating stem by means of which the disk may be screwed to position, and said handle having an interior 115 chamber to pass downwardly over said stem.

3. A lather brush comprising a bunch of 120 bristles or the like having a knot-end encompassed by a metal band, a ferrule having an inner screw thread and in its lower portion a seat for said band, a threaded flat binding disk screwed into the lower portion 125 of said ferrule against the knot of the bunch, and a handle having a threaded shank end screwed into the thread of the ferrule at the upper end portion thereof and also a shoulder to engage the upper edge of the 130 ferrule and arrest said shank end above said disk, said disk having a central upwardly extending operating stem by means

of which the disk may be screwed to position and which stem when the disk is in position projects above said ferrule, and said handle having an interior chamber to pass downwardly over said stem.

4. A lather brush comprising a bunch of bristles or the like having a knot-end encompassed by a metal band, a ferrule having an inner screw thread and in its lower portion a seat for said band, a threaded flat binding disk screwed into the lower portion of said ferrule against the knot of the bunch, and a handle having a threaded

shank end screwed into the thread of the ferrule at the upper end portion thereof and 15 also a shoulder to engage the upper edge of the ferrule and arrest said shank end above said disk, said disk having a central upwardly extending operating stem having in its upper end a screw-driver slot and by 20 means of which the disk may be screwed to position.

Signed at New York city, in the county of New York and State of New York, this 6th day of July, A. D. 1922.

MARCUS B. BEHRMAN.
